CLAIM

The ornamental design for a mounting element of a dashboard vent mount for an electronic device, as shown and described.

DESCRIPTION

FIG. 1 is an elevation view of the mounting element of a dashboard vent mount for an electronic device;

FIG. 2 is a plan view of the top of the mounting element of a dashboard vent mount for an electronic device;

FIG. 3 is an elevation view of the left side of the mounting element of a dashboard vent mount for an electronic device;

FIG. 4 is an elevation view of the right side of the mounting element of a dashboard vent mount for an electronic device;

FIG. 5 is a plan view of the bottom of the mounting element of a dashboard vent mount for an electronic device; and,

FIG. 6 is an isometric view of the mounting element of a dashboard vent mount for an electronic device.

The broken line portion of the figure drawings, which illustrate a clamping element portion of a dashboard vent mount for a portable electronic device, is included to show unclaimed subject matter only and forms no part of the claimed design.
